Primary Examiner — Ruth McInroy(74) *Attorney, Agent, or Firm* — Bereskin and Parr LLP/S.E.N.C.R.L., s.r.l.(57) **CLAIM**

The ornamental design for a portable grill, as shown and described.

DESCRIPTION

FIG. 1 is a perspective view of a portable grill showing the top, right, and front of our new design.

FIG. 2 is a front view thereof.

FIG. 3 is a right view thereof.

FIG. 4 is a back view thereof.

FIG. 5 is a left view thereof.

FIG. 6 is a top view thereof.

FIG. 7 is a bottom view thereof.

FIG. 8 is another perspective view thereof with environmental structures.

FIG. 9 is another front view thereof with environmental structures.

FIG. 10 is another right view thereof with environmental structures.

FIG. 11 is another back view thereof with environmental structures.

FIG. 12 is another left view thereof with environmental structures.

FIG. 13 is another top view thereof with environmental structures; and,

FIG. 14 is another bottom view thereof with environmental structures.

The broken line showing of FIGS. 7 and 14 is for the purpose of illustrating a boundary of the claimed design and forms no part of the claimed design.

The broken line showing of FIGS. 1-14 is for the purpose of illustrating environmental structures and forms no part of the claimed design.
